UNITED STATES PATENT OFFICE.

OSCAR LEROY GLASER, OF OAK PARK, ILLINOIS.

PUMP.

1,209,833.

Specification of Letters Patent. Patented Dec. 26, 1916.

Application filed April 26, 1915. Serial No. 23,806.

To all whom it may concern:

Be it known that I, OSCAR L. GLASER, a citizen of the United States, residing at Oak Park, in the county of Cook and State of Illinois, have invented certain new and useful Improvements in Pumps, of which the following is a specification.

My invention relates to improvements in pumps, and has for its general object to provide an improved and efficient air pump as may conveniently be used for the inflation of automobile tires, as well as other uses.

Among the objects of my invention are to provide a construction that is simple, cheap, durable, efficient, easily repaired, effectively lubricated, and positive in its pumping action.

Other objects of my invention are to provide a construction that will operate effectively at low shaft speed, and handle a large volume of air in proportion to its size.

In the drawings wherein I have illustrated an embodiment of my invention Figure 1 is a vertical cross section of a pump embodying my invention; Fig. 2 is a plan view thereof. Fig. 3 is a vertical cross section on line 3—3 of Fig. 1 and Fig. 4 is a transverse section on line 4—4 of Fig. 1.

The pump shaft 10 carried by bearings 11 and 12 in the side walls of the casing, carries a cam structure 13 that coats with a roller 14 carried by the pump piston 15, a spring 16 holding the roller constantly in contact with the cam. The piston works in the cylinder portion 17 of the frame structure 18 that has, opening to a cylinder clearance space an outlet port 19, and inlet ports 20 and 21. The pump structure is preferably condensed in height, and constructed with a cylinder portion having a bore much larger than the stroke, the relation shown being somewhat more than 3 to 1.

The upper portion of the casing 18, in which the piston reciprocates, is provided with radiating ribs 23, preferably horizontally disposed, but stopping short of the end of the cylinder, the end of the cylinder portion being externally reduced and screw-threaded as at 24 to receive the head or cap 25 in which the ports 19 and 21 are located. Said head is provided with radiating ribs 23' at its sides, and across its top is preferably provided with further ribs 23'' that radiate from the centrally located boss 19' 55 through which port 19 is made. This boss is chambered as at 26 to contain a ball valve

27 for closing, inwardly, the port 19, inward pressure being exerted on the valve by spring 28 that bears against the nipple 29 threaded into the end of the boss and itself 60 having a threaded orifice 29' for connection with an air pipe. A valve for the intake port 21 is reversely arranged, boss 21' suitably chambered, being provided with a nipple 31 in which is formed a seat for ball 65 valve 32 pressed outwardly by spring 33. The intake ports 20 are preferably made at intervals all around the cylinder, at substantially the lowest level reached by the piston in its stroke.

The cylinder frame 18 preferably continues downward of uniform diameter below the bearings 11 and 12 and shaft 10, and is provided with bosses 11' and 12' for the respective bearing bushings, boss 11' being preferably arranged exteriorly to the cylinder and boss 12' interiorly of the frame, the shaft continuing to the exterior of the device on the first mentioned side and stopping in the bearing 12'. Below the bearing 70 75 80 the cylindrical frame is preferably reduced in diameter as at 18' to form an oil well 35 that is closed at its bottom by a screw cap 36, and cleats 37—37 are provided, with bearing surfaces below the cap 36, and with bolt 85 90 95 openings 38 suitably formed therein, for support of the structure.

The piston 15 is preferably made hollow, with inwardly projecting lugs 15' flanking the roller 14, and affording bearing for the 90 roller shaft 40 that on one side preferably projects in an extension 40' through a slot 41 in the side wall of the frame and into a spring chamber 42. The side and end walls of the spring chamber are preferably 95 cast integral with the frame, and a removable cover 42 is screw fastened to said walls to close the face of the chamber. The spring 16 has one end connected with the groove 44 in the shaft extension 40', its other end being connected to a boss 45 at the bottom of the chamber, which is preferably below the level of the main shaft 10. An oil duct 46 preferably leads from the bottom of the spring chamber into the oil well 35.

The cam 13 coating with roller 14 is preferably made with three lobes 13', each having its surfaces concavely curved at their sides and rounded at the top so as to tend to maintain the contact point between cam 110 and roller close to the lowest point of the roller for direct application of thrust, and

shaped to give the piston, through the roller, a gradual rise in the early part of its instroke, and more rapid displacement at the finishing portion of its instroke, with a reversal of this action as to the outstroke. For purposes of lubrication a body of oil is maintained in the chamber 35.

It will be apparent that each rotation of the shaft 10 will result in three reciprocations of the piston, giving, on account of the large bore of the pump, a great volumetric displacement of air. On the piston instroke the compression, augmenting as the piston rises, lifts the valve 27 to force air out through the orifice 29', the rapid rise of the piston near the end of its stroke giving an impulsive quality to the final air delivery that is very effective in overcoming the resistance that is offered by an almost-inflated tire. The multiple lobe cam, working in the oil containing chamber, effects an adequate splash lubrication of all the working parts, such surplus oil as splashes into the spring chamber returning to the oil well through the duct 46. On the outstroke of the piston the valve 32 opens promptly to admit air, in order that the spring 16 may not be working against the vacuum tendency materially resisting the return of the piston, and when the piston reaches its limit of outstroke, the opening of the extensive area port 22 completely fills the cylinder with air, so that even if the speed of operation of the pump has required admission of air in excess of the capacity of port 21, the displacement of the full volume of air on the next instroke is assured.

Having described my invention, what I claim is:

1. In a pump, a casing having a cylinder portion at one end and an oil well portion therebelow, a main shaft traversing said casing between said portions, a multiple lobe cam on said shaft, a piston in the cylinder provided with a roller for coaction with said cam, a spring chamber external to said casing but in open communication therewith, there being an oil return duct from said spring chamber to said oil well portion of the casing, and a spring in said casing acting on said piston constantly to maintain it in coaction with its cam.
2. In a pump the combination of a cylinder, a hollow cup shaped piston therein, a pin mounted at its end portions in opposite walls of the piston and projecting at one end through a vertical slot in the cylinder wall, a roller journaled on said pin within the piston, a drive shaft parallel with said

pin, a cam on said shaft contacting with the roller, and a spring positioned outside of the cylinder and secured at one end to the projecting end of the aforesaid pin to maintain the roller in contact with the cam. 65

3. In an air pump the combination of a frame providing a cylinder portion, a chamber below said cylinder portion, and an external spring chamber, having communication with the chamber below the cylinder, 70 through a slot 41, a main shaft, a cam thereon, a piston, a roller for coaction with the cam, a shaft connecting said roller with the piston and extending through said slot 41 into the spring chamber, a spring in said 75 chamber acting on the shaft extension to maintain the roller in contact with the cam, and a removable cover plate for said spring chamber.

4. A large bore, short stroke air pump, 80 the operating parts of which are completely inclosed, comprising a one piece frame, open at its lower and upper ends and providing in its upper end a cylinder, a piston reciprocable therein, a cylinder head secured on the upper end of the frame, a closure plug secured to the opening in the lower end of the frame, opposite shaft bearings in the side walls of the frame, a straight shaft of uniform diameter journaled in said bearings, a roller carried by the piston, a piston actuating cam mounted on the shaft for engagement with the roller and means for maintaining the roller in engagement with the cam. 90

5. A large bore, short stroke air pump, the operating parts of which are completely inclosed, comprising a one piece frame, open at its upper and lower ends and providing in its upper end a cylinder, a hollow cup 100 shaped piston reciprocable therein, a cylinder head screw threaded over the upper end of the frame, a closure plug screw threaded into the opening in the lower end of the frame, opposite shaft bearings in the side 105 walls of the frame, a straight shaft of uniform diameter journaled in said bearings, a roller journaled within the cup shaped piston, a roller actuating cam mounted on the shaft within the frame, whereby the 110 piston is reciprocated by rotation of the shaft and means for maintaining the roller in engagement with the cam.

In testimony whereof I hereunto set my hand in the presence of two subscribing witnesses. 115
